(57) **CLAIM**

The ornamental design for a model vehicle underbody light assembly as shown and described.

DESCRIPTION

FIG. 1 is an upper, left, front perspective view of a model vehicle underbody light assembly showing our new design; FIG. 2 is an upper, right, rear perspective view thereof; FIG. 3 is a lower, right, front perspective view thereof; FIG. 4 is a lower, left, rear perspective view thereof; FIG. 5 is a front elevation view thereof; FIG. 6 is a rear elevation view thereof; FIG. 7 is an upper plan view thereof; FIG. 8 is a lower plan view thereof; FIG. 9 is a right-side elevation view thereof; and, FIG. 10 is a left-side elevation view of a model vehicle underbody light assembly.

In the drawings, the broken lines illustrate portions of the model vehicle underbody light assembly that form no part of the claimed design.
